TENPIN

Arnold W. Walker, Detroit, Mich., assignor of
one-half to Fred Schultz, Detroit, Mich.

Application April 19, 1939, Serial No. 268,831

1 Claim. (Cl. 273—82)

The invention relates to a bowling pin and more especially to a bowling pin base, the pins being commonly termed tenpin.

The primary object of the invention is the provision of a pin of this character wherein its base is fastened to the bottom end of the said pin with the fastening concealed interiorly thereof and interlocked with the pin and base so that there is no liability of the separation of the base from the pin proper irrespective of hard usage in the playing of a bowling game with the pins in use therein.

Another object of the invention is the provision of a pin of this character wherein the base and the manner of fastening the same to the body of the pin are novel, the fastener being entirely concealed from view and the base will be firmly and permanently attached so that impact upon the pin will not disturb or cause the fasteners to work loose with resultant loss of the base from the body of the pin.

A further object of the invention is the provision of a pin of this character wherein the base is made from fibrous material and is interfitted with the body of the pin while the fastener interlocks the base and body together, the fastening of the base upon the pin avoiding the use of screws, nails or other like fasteners.

A still further object of the invention is the provision of a pin of this character which is simple in construction, thoroughly reliable and effective in operation, assured of increased life and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention and pointed out in the claim hereunto appended.

In the accompanying drawing:

Figure 1 is an elevation of a pin constructed in accordance with the invention.

Figure 2 is a horizontal sectional view through the pin and its base.

Figure 3 is a fragmentary side elevation on enlarged scale showing the base removed.

Figure 4 is a fragmentary vertical longitudinal sectional view showing in detail the base permanently fastened to the body of the pin.

Similar reference characters indicate corresponding parts throughout the several views in the drawing.

Referring to the drawing in detail, A designates generally a bowling pin which is of standard construction except that its body 10 at the lower end thereof is formed with a central reduced portion 11 constituting concentrically thereto an annular seat for a fibrous ring-like base 12. This base 12 at the outer periphery thereof conforms to the contour of the body 10 at the external surface of the same and such base snugly fits the reduced central portion 11 to be disposed concentric thereto.

This central reduced portion 11 has formed therein an annular channel or groove 13 while formed in the base 12 is an annular companion groove or channel 14, these grooves or channels 13 and 14 being receptive of a fastener in this instance in the form of a springy substantially square shape frame 15 preferably made from a single length of inherently resilient wire and the corners 16 of this frame are adapted to protrude into the channel or groove 14 of the base 12 while the portions of the frame intermediate of the corners thereof intersect the channel or groove 13 in the central reduced portion 11 of the body 10 of the pin. In this manner the base 12 is permanently fastened to the body to be concentric to the portion 11 thereof at the lower end of said pin and the fastener securing the base 12 in place is concealed thereby and also by the portion 11. The base 12 is permanently fastened in that the fastener is interlocked with the portion 11 and the said base.

By reason of the mode of fastening the base 12 with the pin body 10 avoids the necessity of the use of nails or screws and shocks imparted to the pin A through ball contact therewith cannot possibly loosen the base 12 from the body 10, the said base being permanently held fixed to the body of the pin throughout the life of the latter.

What is claimed is:

In a pin of the character described, a body having a reduced longer end, a ring-like base concentrically about the reduced end and having an outer face substantially flush with the outer face of said reduced end, the end and base being formed with matched intercommunicating annular channels at confronting faces thereof, and an inherently springy straight-sided frame having corner portions received at spaced intervals at one channel and the straight sides seated in the other channel.

ARNOLD W. WALKER.
